EXPANSIBLE CHAIN

Eugen Prestinari, Short Hills, and John F. Sand,
Newark, N. J., assignors to Gemex Company,
Union, N. J., a corporation of New Jersey

Application June 4, 1951, Serial No. 15,412

Term of patent 7 years

(Cl. D45—4)

To all whom it may concern:

Be it known that we, Eugen Prestinari and John F. Sand, citizens of the United States and residents of Short Hills, Essex County, New Jersey and Newark, Essex County, New Jersey, respectively, have invented a new, original, and ornamental Design for an Expansible Chain, of which the following is a specification, reference being had to the accompanying drawing, forming part hereof, in which

Fig. 1 is a top plan view of an expansible chain, embodying my new design, the chain being shown in fully contracted condition;

Fig. 2 is a top plan view of the chain in an expanded condition, portions of the conventional appearing bottom links of the chain being visible between the expanded top links;

Fig. 3 is a side view of one of the top links;

Fig. 4 is an end view of one of the top links;

Fig. 5 is a section taken on line 5—5 of Fig. 3; and,

Fig. 6 is a perspective view of one of the top links.

We claim:

The ornamental design for an expansible chain, substantially as shown and described.

EUGEN PRESTINARI.
JOHN F. SAND.
